UNITED STATES PATENT OFFICE

2,038,920

SURFACE FINISHING PANEL

Frank Bishop, Los Angeles, Calif.

Application July 26, 1929, Serial No. 381,268

25 Claims. (Cl. 72—23)

This invention relates to a method of forming wall surfaces and to surface finishing elements and particularly pertains to tile and panels of tile for covering walls and similar surfaces to form a tile surface.

An object of the invention is to provide a tile formed with a body of sheet-like material, such as sheet metal, in which the body is adapted to be readily applied to form a surface covering. Another object is to provide a metallic tile having a mechanical fastening means for affording a connection between the tile and a surface to which it is applied and which fastening means is especially adapted for engagement with a fibrous backing whereby the tile may be readily applied to surfaces formed of wood or composition boards.

Another object is to provide a preformed surface finishing panel including a series of assembled tile units on a backing panel or foundation sheet which is adapted to be assembled or manufactured in the shop in sizes to fit dimensioned areas of wall surfaces and thereafter be applied to a wall surface or other supporting structure in one or a number of pieces as occasion may require, with each piece embodying a series of assembled tile units, thereby obviating the necessity of assembling the tile units on the wall surface as now generally practiced, and thus effecting a great economy in labor in covering a surface with tile.

Another object is to provide a surface covering panel of the above character in which tile sections are so formed and mounted on a backing panel that a plastic or cementitious material may be interposed between the main body portions of the tile sections and the backing panel and in grooves or channels between contiguous tile sections after assemblage of the sections on the backing panel.

Another object is to provide an effective means for anchoring the metallic tile sections on the backing panel so formed as to facilitate assemblage of the tile sections on the panel.

Another object is to provide a process or method of producing tiled units whereby a multiplicity of tiles may be seated on a backing panel in a predetermined relationship to be finally occupied, and simultaneous application of a multiplicity of the tiles to the backing panel be effected.

Another object is to provide a process of producing preformed tiled panels adapted to application to walls or other supports as a unit, in which a plurality of tiles may be simultaneously affixed to an imperforate backing or foundation.

Another object is to provide a method of constructing a tile surface in which a multiplicity of tiles are initially assembled on a relatively large foundation sheet adapted to be applied to a supporting structure, and in which the construction is such as to permit application of pointing material to grooves between adjacent tiles after applying the foundation sheet to the supporting structure.

Another object is to provide a preformed tile panel as an article of manufacture in which a plurality of tiles are affixed to a backing by means of prongs carried by the tile and in which means are provided associated with the prongs to resist disengagement of the prongs and tile from the backing.

Another object is to provide a means for mechanically attaching tile to a backing together with means for effecting spacing between the faces of adjacent tile and also for effecting spacing between the under side of the face portion of the tile and the backing.

A further object is to provide a tile formed of sheet-like material adapted to be assembled on a foundation with adjacent tile spaced apart embodying means for anchoring plastic pointing material applied in the spaces between the tile.

Another object is to provide a surface finishing tile formed of sheet metal or the like having nailing spurs formed on opposite margins thereof and projecting rearwardly therefrom with the lugs on one margin off-set or staggered relative to the lugs on the other margin in such manner as to eliminate possibility of the lugs of adjacent tile coming together when mounted on a foundation.

With the foregoing objects in view, together with such other objects and advantages as may subsequently appear, the invention resides in the parts and in the combination, construction and arrangement of parts hereinafter described and claimed and illustrated by way of example in the accompanying drawings, in which:

Fig. 1 is a perspective view of a tile unit as seen from the back thereof;

Fig. 2 is a detail in section as seen on the line 2—2 of Fig. 1;

Fig. 3 is a detail in section as seen on the line 3—3 of Fig. 1;

Fig. 4 is an edge view of the tile unit as seen from the upper edge thereof;

Fig. 5 is an end view of the tile unit showing it as applied;

Fig. 6 is a view of the tile unit as seen in front elevation;

Fig. 7 is a view in perspective showing a base unit as seen from the back thereof;

Fig. 8 is a perspective view of a rail unit as seen from the back thereof;

Fig. 9 is a view in front elevation illustrating an assembled panel section embodying a series of tile units;

Fig. 10 is an enlarged detail in section taken on the line 10—10 of Fig. 9 showing the manner of mounting the tile units on a backing panel;

Fig. 11 is a detail in vertical section showing the manner in which spaces between the tile units and the backing panel, and channels between contiguous tile units, may be filled with a plastic or cementitious material, and showing the manner in which the panel sections are affixed to the wall;

Fig. 12 is a detail in section illustrating the manner of finishing the top margin of the panel with a tile rail;

Fig. 13 is a detail in horizontal section showing the manner of forming the ends of the panel sections to afford a finish at outside corners;

Fig. 14 is a detail in section illustrating the manner of forming the assembled panel section to produce a recessed panel effect;

Fig. 15 is a view in perspective illustrating a modified form of the tile anchoring means;

Fig. 16 is a detail in perspective illustrating another modification of the tile anchoring means.

Referring to the drawings more specifically, A indicates generally a tile unit which embodies a face portion B formed of sheet metal and which body portion is here shown as rectangular in outline and as having its edges turned to form narrow marginal flanges including upper and lower flanges 17 and 18 and end flanges 19 and 20. The upper flange 17 is formed intermediate the ends thereof with a tongue 21 which projects in continuation of the flange 17 in a rearward direction and at right angles to the face portion B at the longitudinal center thereof, and formed on the flange 17 equi-distant on opposite sides of the center of the tongue 21 are rearwardly projecting and upstanding lugs 22 and 23. Projecting from the margin of the flange 17 in spaced relation to the lugs 22 and 23 are pointed nailing spurs or prongs 24 and 25 extending in continuation of the flange 17 and spaced apart on opposite sides of the center tongue 21 a greater distance than the spacing of the lugs 22 and 23. A pair of spacing lugs 26 and 27 project rearwardly and upwardly from the flange 17 adjacent to, but spaced from, the ends of the latter.

Formed on the lower flange 18 is a pair of nailing spurs or holding prongs 28 and 29 extending in continuation of the flange 18 at right angles to the face portions B, the centers of which are disposed in alignment with the centers of the lugs 22 and 23, being thus spaced equidistant on opposite sides of the longitudinal center of the face portions B. A pair of lugs 30 and 31 project rearwardly and downwardly from the margin of the flange 18 in spaced relation to the spurs 28 and 29, which lugs are arranged in alignment with the centers of the spurs 24 and 25 on the opposite margin of the face portions B, being thus spaced a greater distance on opposite sides on the center of the face portions B than the spurs 28 and 29. Formed on the flange 18 adjacent to the ends thereof is a pair of outwardly and down-turned flanges 32 and 33, the centers of which are spaced from the centers of the spurs 28 and 29 a distance equal to the

spacing of the centers of said spurs 28 and 29 from each other. The rear faces of the lugs 22, 23, 26, 27, 30, 31, 32 and 33 project on a common plane spaced rearwardly from the edges of the marginal flanges on the face portions B 5 whereby said lugs are adapted to serve as spacers when seating against a surface to which the tile is applied to afford a gap between the marginal flanges of the tile and the surface as indicated at 34 in Fig. 5; and also afford a space between 10 the under side of the face portion B and the surface to which the tile is applied.

The spurs 24, 25, 28 and 29 are adapted to be forced into a backing panel or foundation sheet 35 to which the tile unit is applied as particularly shown in Figs. 5 and 10 and whereby the tile unit is anchored onto the panel.

The lugs 22 and 23 by reason of their being disposed on a plane passing through the spurs 28 and 29, the lugs 22 and 23 on one tile unit 20 may abut against the spurs 28 and 29 of an adjacent unit disposed in alignment therewith, and in like manner the lugs 30 and 31 on one tile unit may abut against the spurs 24 and 25 of an adjacent unit. The lugs 22, 23, 30 and 31 then 25 serve as spacers between contiguous tile units to form grooves or channels 36 between the margins of contiguous units as shown in Figs. 9 and 10; thus affording spaces between the face portions B of adjacent assembled tile units. 30

When the tile units are assembled in broken joint or staggered relation as shown in Fig. 9, the end lugs 32 and 33 will abut against the tongues 21 on an adjacent pair of the tile units arranged therebeneath, whereupon these lugs 35 will then serve as spacers to provide the grooves or channel 36.

By disposing the prongs 24 and 25 on one edge of the tile in staggered or off-set relation to the spurs 28 and 29 on the opposite edge of the tile 40 the possibility of any two spurs of adjacent assembled tile coming together when mounted on a surface is obviated.

The tile units are designed to be assembled on the backing panel 35 as shown in Fig. 9 which 45 panel may be of any suitable dimensions and is designed to be applied to the area to be surfaced with the tile elements assembled thereon; the panel 35 being dimensioned to cover a particular area, and being formed of suitable fibrous material such as laminated wood or composition wall board. 50

An important feature of the invention resides in the fact that the backing or foundation to which the tile unit is applied may be imperforate, that is free of preformed holes or recesses for the reception of the holding spurs since the latter are capable of being pressed or driven into the material of the backing. 55

As a means for affording a finish for the base 60 portions of the finished panels, base units C of tile are provided as shown in Fig. 7; such units being formed with end flanges provided with pairs of spurs 37—38 and 39—40 respectively and with pairs of spacing lugs 41—42 and 43—44 which 65 serve the purposes ascribed to the lugs and spurs of the units A; and as a means for affording a finish at the upper margin of a panel, rail units D are provided as shown in Fig. 8, these sections including spurs 45 and 46 on an inturned lower 70 marginal flange 47, and ears 48 and 49 on an inturned upper flange 50 which ears are adapted to be bent to extend over the back of the panel 35 at the upper margin thereof as shown in Fig. 12.

As a means for affording a finish at outside 75

corners, corner units **E** are provided as shown in section in Fig. 13; these units being formed to extend over the end margin of the panel **35** and having spurs **51** on one margin thereof for engagement with the panel and having ears **52** on the other margin thereof adapted to be bent to extend over the back of the panel.

Where it is desired to form the finished panel with a recessed panel effect the backing panel embodies a layer **53** with a strip **54** planted on the front face thereof to form the backing panel with a raised portion, tile units are imposed on the outer surfaces of said backing and on the strip in the manner before described, and a moulding unit **F** is provided to extend over the margin of the strip **54** projecting from the backing panel **53**, as illustrated in section in Fig. 14; the moulding tile unit being formed with spurs **55** and **56** on its margins engageable with the panel **53** and the strip **54** as shown.

In the form of the invention above described the spurs are formed integral with the tile units but they may be formed as shown in Fig. 15 by spot-welding tacks **57** at suitable points on the back of surface **58** of the tile unit, or a tack **59** may be positioned to extend from the rear face **60** of the tile unit by having the head **61** thereof engaged by an inturned tang **62** on the marginal flange **63** of the tile unit as shown in Fig. 16; the stem of the tack being projected through the tang **62**.

In assembling the finished panel the latter is formed of a dimension to occupy the space to be covered thereby and the several tile units of desired dimensions are planted thereon by pressing the spurs into the back panel to effect driven imbedded engagement therewith. The spurs, which may also be termed penetrating prongs or tangs, are pointed to facilitate their driven or pressed penetration of the backing panel and are of a length greater than the side flanges **17** and **18**, and may be formed of sufficient length to project through the panel in which event the tips of the spurs may be bent or clinched over the back of the panel, as shown at **64** in Fig. 10, thereby effecting a secure engagement between the tile units and the panel. However, the spurs on being forced into the backing panel will serve as nails and will effect such frictional engagement with the material of the panel as to afford a substantial anchorage for the tile units on the panel without such clinching. In either event a mechanical attachment between the spurs and the backing is attained which will resist withdrawing of the spurs and thus resist disengagement of the tile from the backing. In this manner the finished panel may be assembled in the shop and thereafter applied to the surface to be covered.

In applying the assembled panel certain of the tile units may be removed from the panel to permit the driving of nails through the latter into engagement with a nail receiving material as shown in Fig. 11, in which **65** indicates a nailing strip which may comprise wall sheathing or studding or any other wall structure, and **66** designates a nail for effecting connection between the backing panel and the structure **65**. The margins of the backing panel may be secured to the structure **65** by driving nails **67** diagonally therethrough. The removed tile units are then replaced.

After the finished panels have been applied to the wall surface the spaces between the back of the tile units and the backing panel may be filled 75 with a plastic composition **68** which composition

is applied by pouring it into the open spaces **34** extending along the upper margins of the upper row of the tile units, and in order to facilitate filling of the channels **36** between contiguous tile units a sheet **69** of paper or other suitable material is temporarily adhered to the outer surfaces of the tile units to extend over the channels **36** so as to form a mould that will confine the plastic composition in the channels **36**. The plastic material **68** is of a character that is soft or semi-liquid but which will harden when dry. After setting of the plastic filler the sheet **69** is removed.

Where the panels are applied to ceilings or floors the channels **36** may be filled by applying plastic composition or pointing material directly thereto, in which event a bond is afforded between the filler and the tile units by reason of the filler flowing under the edges of the marginal flanges of the tile units and thereby forming a key. In like fashion in forming a wall surface with the preformed sheet having channels between adjacent tile thereon such channels are filled with pointing material after securing the sheets to a supporting structure.

While I have described the tile units as applied to a portable backing panel it is obvious that they may be assembled or set up on a wall surface in the manner employed in applying ordinary tile, excepting that they need not necessarily be set in cement, as the spurs will ordinarily afford sufficient anchorage for the tile units. In this event pointing material will be applied to the spaces between adjacent tile. However, great economy in labor is effected by assembling the tile units on the backing panel in the shop, as in mounting the tile units on the panel a number or multiplicity of the units are initially assembled in the proper position on the panel in the relationship to be finally occupied on the finished panel and they can then be engaged therewith by subjecting the assembled units and panel to pressure as by placing the panel with the units resting thereon in a press and impressing the tile units simultaneously in place. In this manner a considerable number of the tile units may be applied to the backing panel in a single operation.

Manifestly the tile may be formed with any suitable surface finish as is common in the manufacture of metal tile such for example as by applying thereto a surface coating such as enamel, lacquer, porcelain-enamel, and the like.

From the foregoing it will be seen that I have provided a means and method for forming metal covered surfaces in which metallic units are anchored in place on a backing or foundation by penetrating members carried on the units, by a mechanical connection without relying upon the adhesive action of a cement, as is ordinarily practiced in setting metal tile. It will be apparent from the foregoing that by employing the mechanical connection between the tile units and the backing in accordance with the invention as herein set forth, any cement or pointing material employed in conjunction therewith will be held in place by the tile units rather than act to retain such units in place. Although such cement may assist holding the units in place, it primarily serves the purpose of sealing the joint between the adjacent tile units. It will also be seen that I have produced as an article of manufacture, a panel or sheet having tile characteristics, which can be readily assembled and set in place on a supporting structure, and which when applied will have the appearance of ordinary tile.

I claim:

1. A surface finishing tile comprising a metallic plate, nailing spurs formed on the margin of said plate, and spacing lugs on the margin of said plate operable to space the plate from a surface to which it is applied and to cooperate with spurs on the margins of the contiguous plate to space adjacent plates apart. 5
2. A surface finishing tile embodying a metallic plate having marginal flanges, nailing spurs formed integral with said flanges and projecting rearwardly from said plate, and spacing lugs formed integral with said flanges projecting rearwardly from said plate and having their ends projecting beyond the margins of the plate. 10
3. In a surface finishing tile, a sheet metal plate, a nailing spur on one margin of said plate and projecting rearwardly therefrom, and a spacing lug on the other margin of said plate extending in alignment with said nailing spur. 15
4. A surface finishing panel comprising a fibrous backing panel, a series of metallic tile units on said backing panel, and means affixed to and projecting from the back of each of said tile units for fastening said tile units to said panel there being marginal spacing lugs provided upon said tile units to maintain contiguous units in spaced relation to each other. 20
5. A surface finishing panel comprising a fibrous backing panel, a series of metallic tile units covering said panel, nailing spurs on each of said tile units penetrating said backing panel, and spacing lugs on each of said tile units operable to space the body portions of the units from the backing panel. 25
6. A surface finishing panel comprising a fibrous backing panel, a series of metallic tile units covering said panel, nailing spurs on each of said tile units penetrating said backing panel, and spacing lugs on each of said tile units operable to space the body portions of the units from the backing panel and operable to space contiguous tile units from each other. 30
7. A surface finishing panel comprising a fibrous backing panel, a series of metallic tile units covering said panel, nailing spurs on each of said tile units penetrating said backing panel, spacing lugs on each of said tile units operable to space the body portions of the units from the backing panel, and a hardened plastic composition interposed between the tile units and the backing panel. 35
8. A surface finishing panel comprising a fibrous backing panel, a series of metallic tile units covering said panel, nailing spurs on each of said tile units penetrating said backing panel, spacing lugs on each of said tile units operable to space the body portions of the units from the backing panel and operable to space contiguous tile units from each other and a hardened plastic material filling the spaces between contiguous tile units. 40
9. A surface finishing tile embodying a metallic plate having marginal flanges, spacing lugs on said flanges for spacing said plate from a surface to which it is applied, and pointed nailing spurs formed integral with said flanges and projecting rearwardly from said plate for driving into a surface to which said plate is applied. 45
10. A surface finishing panel comprising as an article of manufacture, a fibrous backing panel, a series of metallic tile units on said backing panel having spacing members extending between the margins of said units and said panel, and nailing spurs integral with said flanges and protruding therefrom, said spurs penetrating said backing panel and mechanically fastening said tile units 50
- to said panel by direct frictional engagement therewith. 55
11. A surface finishing panel comprising as an article of manufacture, a fibrous backing panel, a series of metallic tile units on said backing panel having a plurality of integral nailing spurs formed thereon, said spurs penetrating said backing panel in direct frictional engagement therewith and mechanically fastening said tile units to said panel. 60
12. A metallic tile unit having a plurality of pointed nailing spurs carried on opposite margins thereof and projecting rearwardly therefrom for effecting penetration of and direct frictional engagement with a backing to which said unit is applied; the spurs on one margin of the unit being staggered relative to the spurs on the other margin thereof. 65
13. A surface finishing panel comprising as an article of manufacture, a fibrous backing panel, a series of metallic tile units on said backing panel having a plurality of nailing spurs formed thereon, said spurs penetrating said backing panel in direct frictional engagement therewith, and having their ends clinched over the back of said panel to resist disengagement of said tile units from said panel. 70
14. A surface finishing panel comprising as an article of manufacture, a fibrous backing, a series of metallic tile units on said backing having a plurality of nailing spurs formed thereon, said spurs penetrating said backing in direct frictional engagement therewith, and having their ends clinched over the back of said backing, and means associated with said spurs spacing the under sides of said units from said backing. 75
15. A surface finishing tile comprising a metallic plate, rearwardly projecting marginal flanges on said plate, penetrating holding spurs protruding rearwardly from said plate a greater length than said flanges, and lugs on said flanges for spacing the margins of said flanges from a backing to which the tile is applied. 80
16. A preformed tile panel adapted to be applied to a wall or similar surface as a unit, comprising a backing sheet and a plurality of tiles mechanically attached thereto, said tiles being formed of sheet-like material having face portions, side flanges and penetrating holding prongs of greater length than said side flanges, said tiles being applied to one face of said backing sheet in predetermined relationship with spaces between said face portions of adjacent tiles and between the under sides of said face portions and said backing sheet, said prongs having a driven imbedded engagement within said backing sheet and means associated with said prongs resisting withdrawing movement of said prongs and tiles. 85
17. The process of producing a tiled unit consisting of a backing panel having a multiplicity of tiles on the face thereof, each of said tiles having tangs extending into the panel, which consists in assembling the multiplicity of tiles with the tangs thereof presented to the panel, and then forcing the panel and assembled tiles together to cause the tangs to be forced into the panel. 90
18. The process of producing preformed tile panels adapted for application to a wall or similar surface as a unit, which comprises providing a plurality of tiles formed of sheet-like material, having face portions, side flanges, and penetrating holding prongs of greater length than said side flanges, providing an imperforate backing sheet, arranging said tiles in the relationship to be finally occupied on the finished panel, with the 95

prongs presented to said backing sheet, forcing said backing sheet and tiles together, causing said prongs to penetrate said backing sheet to simultaneously attach all of the assembled tiles to said 5 backing sheet in their final positions.

19. The process of producing a tiled unit consisting of a backing panel having a multiplicity of tiles on the face thereof, each of said tiles having tangs extending into the panel, which consists in assembling the multiplicity of tiles with the tangs thereof presented to the panel, then forcing the panel and assembled tiles together to cause the tangs to be forced into the panel, and then clinching said tangs against the back of 10 said backing sheet.

20. The process of producing preformed tile panels adapted for application to a wall or similar surface as a unit, which comprises providing a plurality of tiles formed of sheet-like material, 20 having face portions, side flanges, and penetrating holding prongs of greater length than said side flanges, providing an imperforate backing sheet, arranging said tiles in the relationship to be finally occupied on the finished panel, with the 25 prongs presented to said backing sheet, forcing said backing sheet and tiles together, causing said prongs to penetrate said backing sheet to simultaneously attach all of the assembled tiles to said backing sheet in their final positions, and then clinching said prongs against the back of said 30 backing sheet.

21. The method of constructing a tiled surface which consists in covering a relatively large foundation sheet with a multiplicity of porcelain-enamelled sheet-metal tiles spaced apart to provide grooves therebetween, then securing said sheet to a supporting structure, and then applying pointing material to said grooves.

22. An article of manufacture consisting of a preformed tiled panel adapted to be applied to a wall or similar surface as a unit, comprising a backing sheet and a plurality of tiles mechanically attached thereto, said tiles being formed of 5 sheet metal having face portions, side flanges and holding prongs of greater length than said side flanges, said tiles being applied to one face of said backing sheet in predetermined relationship with spaces between said face portions of adjacent tiles 10 and between the under sides of said face portions and said backing sheet, said prongs extending into said sheet and being clenched to resist withdrawing movement of said prongs and tiles, the spaces between said face portions of adjacent tiles 15 constituting grooves to receive pointing material.

23. The combination of a foundation sheet and a multiplicity of tiles covering one face of the sheet, each tile consisting of a sheet-metal plate having marginal flanges and tangs on the flanges, 20 said flanges bearing against the sheet and said tangs entering the sheet, and means associated with said tangs to resist disengagement of the tile from the sheet.

24. A surface finish tile embodying a plate, 25 holding prongs on said plate formed to effect penetration of and mechanical engagement with an imperforate backing, and spacing members on said plate arranged to space the margins thereof from the backing on which it is applied. 30

25. The combination of a fibrous backing, a plurality of sheet tile mechanically attached to said backing with grooves between adjacent tile and with spaces between the under side of the tile and the backing, and plastic material filling 35 said grooves and extending into said spaces and engaged by the margin of said tile.

FRANK BISHOP.
